Specification for Design.

Patented Oct. 5, 1920.

Application filed January 20, 1920. Serial No. 352,864. Term of patent 3½ years.

To all whom it may concern:

Be it known that I, HERMAN BAECHTOLD, a citizen of Switzerland, and residing at the city of New York, borough of Queens, in the county of Queens and State of New York, have invented a new, original, and ornamental Design for Lace, of which the following is a specification, reference being had to the accompanying drawing, forming part thereof.

The figure is a plan view of one repeat of lace showing my new design.

I claim:

The ornamental design for lace as shown.

HERMAN BAECHTOLD.
